(57) **CLAIM**

The ornamental design for defeater latch handle, as shown and described.

DESCRIPTION

FIG. 1 is perspective view of defeater latch handle showing my new design;

FIG. 2 is a right side view of the defeater latch handle of FIG. 1.

FIG. 3 is front view of the defeater latch handle of FIG. 1.

FIG. 4 is rear view of the defeater latch handle of FIG. 1.

FIG. 5 is a top view of the defeater latch handle of FIG. 1; and, FIG. 6 is a bottom view of the defeater latch handle of FIG. 1. The left side view of the defeater latch handle is a mirror image of the right side view of the defeater latch handle of FIG. 2.

The features shown in dashed lines form no part of the design and are not claimed.
